UNITED STATES PATENT OFFICE.

ERNEST W. SNOW, OF ROCHESTER, NEW YORK.

GUTTER-BOX.

1,032,249.

Specification of Letters Patent.

Patented July 9, 1912.

Application filed October 31, 1910. Serial No. 589,990.

To all whom it may concern:

Be it known that I, ERNEST W. SNOW, a citizen of the United States, residing at Rochester, in the county of Monroe and State of New York, have invented certain new and useful Improvement in Gutter-Boxes, of which the following is a specification.

This invention relates to an improvement in distributing boards for electrical conduits.

The primary object of said invention is to provide a panel or distributing board with an outside "gutter" formed of cast iron or sheet metal which is provided with a removable cover through which the wires may be inserted and openings adapted to connect the box or panel with the "gutter" for the purpose of distributing the electric wires on said panel.

It has heretofore been the practice to arrange the "gutter" on the inside of the distributing box and the object of this invention is to construct a device which will be more efficient than the distributing boxes now in use and which will be cheaply and easily constructed, the arrangement being such as to greatly reduce the size of the box which will not only allow the device to be more cheaply manufactured but will at the same time form a box which will take up considerably less room than the boxes now in use.

In the drawings:—Figure 1 is a view of the distributing box showing the arrangement of the "gutters". Fig. 2 a sectional view taken on the line 1—1 of Fig. 1. Fig. 3 a view showing a slightly modified form of "gutter" box. Fig. 4 is a view showing a distributing box provided with "gutters" arranged in series, the "gutters" being provided with a switch mechanism. Fig. 5 a sectional view of said box. Fig. 6 a detailed view showing the manner of feeding the wires to the distributing box. Fig. 7 a detailed view of one of the closures. Fig. 8 a detailed view showing a slightly modified form of closure.

In the drawings: 10 designates the distributing box which is provided with the usual distributing panel 11. In the form shown in Fig. 1 the "gutter" consists of the casing 12 which is formed with one open side which is arranged to lie flush with the box 10, the casing being clamped to said box by screws 12' which pass through aper-

tures 12". The casing is also provided with the beveled portion 13 which has arranged thereon an aperture 14. Pipes 15 are connected to said casing, through which the wires are adapted to extend. The wall of the distributing box is provided with a plurality of apertures in which are inserted the insulated bushings 16 through which the wires are adapted to pass in entering the box.

It will be seen that the wires may be first inserted within the pipes 15 and then pass through the bushings 16 and be connected up with the distributing board, the wires being handled through the opening 14 in the casing. A plate 17, as best seen in Figs. 7 and 10, is adapted to cover said opening, said plate being provided near one edge with a lug 18 arranged at such an angle thereto as to engage the inner face of the casing 19. Arranged at an angle on the opposite edge of the plate is a perforated lug 18' to receive a retaining screw in such a manner as to engage the casing at the opposite edge of the opening, thereby holding the cover against removal.

The distributing box is provided with a "gutter" adapted to receive the wires and a "gutter" through which the wires may be passed in order to conduct the wires from the box.

In the form shown in Fig. 4 the "gutters" are arranged in pairs, a snap switch 26 being arranged on the intake "gutter", the wires being connected to said switch before the same enter the distributing box. It will be noted that the outlet "gutter" as shown in this form consists of the shell 20 which has formed integral therewith the hollow extension 21 through which the wires are adapted to pass, said extension being screw-threaded to receive a conductor carrying pipe.

In the modified form of closure 17' shown in Figs. 8 and 9 slidably arranged latches 24 are connected by means of the links 24' with the elliptical plate 25 which is rotated by means of the pin 25'. These sliding plates have their free ends beveled and are adapted to engage the interior of the "gutter" to securely hold the closure against accidental displacement.

What is claimed is:

1. In a gutter box, a plurality of casings secured to said box, said casing and box being provided with registering openings,

bushings arranged in said box openings, each of said casings having the adjacent portions of two of the contiguous sides removed to provide an access opening, said casings being provided with removable covers for said access openings forming obtuse angles with the walls of said casings, sliding means carried by said covers, for engagement with the adjacent walls of said access openings, to hold the same in contact with the said casings, and means for projecting the sliding means beyond the edges of the covers and for retracting the same.

2. In a gutter box, the combination with a plurality of casings secured to said box, having access openings, of removable covers

for said access openings and forming obtuse angles with the walls thereof, blocks slidably mounted on each of the covers, an apertured rotatable elongated block therebetween, and links connected to the sliding blocks and the rotatable block, said cover having an opening to permit the insertion of an instrument into the block opening, whereby the elongated block may be rotated to extend or retract the sliding blocks.

In testimony whereof I affix my signature, in the presence of two witnesses.

ERNEST W. SNOW.
